UNITED STATES PATENT OFFICE.

JOHN H. STONEMETZ, OF ERIE, PENNSYLVANIA.

PAPER-FOLDING MACHINE.

SPECIFICATION forming part of Letters Patent No. 299,094, dated May 20, 1884.

Application filed May 19, 1883. (No model.)

To all whom it may concern:

Be it known that I, JOHN H. STONEMETZ, a citizen of the United States, residing at Erie, in the county of Erie and State of Pennsylvania, have invented certain new and useful Improvements in Conveying Devices for Paper-Folding Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to a sheet-conveying mechanism for paper-folding machines, or to devices interposed between a printing-press and folding-machine for conveying sheets of paper from the former to the latter. A mechanism heretofore devised by me for this purpose consists of a table or frame that is connected with the folding-machine, and has carrier tapes or bands passing over rollers at the top of said table or frame and around rollers on the folding-machine, which serve to give motion to said tapes. It has been found that these traveling tapes or bands frequently fail to perform their work, or do not work satisfactorily, chiefly by reason of a want of proper adhesion between the tapes and the paper, thus causing the stoppage or retarded movement of the latter. In the present invention I use all of the devices above referred to, and combine therewith milled or corrugated wheels or disks, which are fitted on one of the upper guide-rollers of the conveyer-tapes in proximity to the delivery end of the printing-press. The face speed of these milled or corrugated wheels or disks is faster than that of the conveyer-tapes, so that said wheels will always propel or feed the paper along and prevent it from stopping or being retarded in its movement while in transit between the press and folding devices.

In the drawings, Figure 1 is a side view of my improved sheet-conveying attachment for paper-folding machines. Fig. 2 is a top view of the same. Fig. 3 is a detail sectional view of the milled feeding-wheel and supporting-bracket.

The letter A designates the delivery end of the frame of a printing-press, and B indicates

a paper-folding machine, having a sheet-conveying attachment bridging the space between the same and the press. This attachment consists of an inclined board or table, C, that is connected with the folding-machine frame by hinges, or otherwise. At the upper end of this board or table is arranged a horizontal transverse roller, D, and in juxtaposition thereto another roller, E. These two rollers are journaled in supporting-brackets F, which are secured at the upper end of the board or table C, as is shown in Figs. 2 and 3. The upper roller, D, or the one nearest to the printing-press, has a series of milled or corrugated wheels, disks, or sections, G, which project above the tape-bearing surfaces of said roller, these surfaces being formed by the smooth portions of the roller located between the corrugated or milled disks G. The set of tapes H extend around the aforesaid roller D and travel over and under the board or table C, being passed at the bottom around a driving-roller on the folding-machine. Another set of tapes, I, operate altogether above the board C, and are conducted around the roller E thereof and a roller on the folding-machine. The tapes I run from a point somewhat in advance of the tapes H, and thus a "nip" or space is left between both sets of tapes, into which the paper from the printing-press is fed by the action of the milled wheels or disks G. It will be understood that the sheets coming from the press pass over the milled or corrugated disks or enlarged portions of the roller D, and as the face speed of said disks is greater than that of the conveyer-tapes operating between said disks it follows that if the tapes should fail to move the paper forward in a regular manner the milled disks will still perform their function of moving the paper forward at a regular and uniform rate of speed. The clogging or retarded movement of the paper between the conveyer-tapes is in this manner, or by the use of the milled disks or corrugated enlargements of the tape-roller, prevented by most simple and effective means. The projecting ridges of the milled disks catch the edge of the advancing sheet and straighten it out, if it is not straight and true, so that it enters between the tapes H and I without any tendency to double back on itself.

I am aware that milled folding-rollers have

been used on paper-folding machines in connection with conveyer-tapes; but the faces of the milled surfaces have always been flush with the tape-conveying surfaces, so that they have 5 had the same surface speed.

By making the milled surfaces of the roller of a larger diameter than the portions around which the tapes pass I secure a slightly faster surface speed than is possessed by the tapes, 10 and cause the former to project beyond the latter, as above described, so that they have a certain grip on the paper.

Although this device may be applied to the other tape-conveyer rolls of a folding-machine, 15 yet it is of special value at the place above described, where the sheet of paper is just passing from the printing to the folding machine. After the sheet has fairly entered on its course through the folding-machine it is 20 rarely checked or retarded.

Having thus described my invention, what I claim as new, and desire to secure by Letters Patent, is—

1. In a paper-folding machine, the combi-

nation, with a system of conveyer-tapes, of a 25 roller having milled or corrugated disks or sections of a larger diameter than the tape bearing or supporting surfaces of said roller, whereby the milled sections of the roller project beyond the tapes and have a faster surface speed, 30 substantially as and for the purpose set forth.

2. In a sheet-conveying attachment for paper-folding machines, the combination, with a board or table having a system of conveyer-tapes and adapted to bridge the space between a folding-machine and printing-press, of an upper tape-guiding roller having milled or corrugated disks or sections of a larger diameter than the tape bearing or supporting surfaces of said roller, substantially as and for the purpose herein set forth. 35 40

In testimony whereof I affix my signature in presence of two witnesses.

JOHN H. STONEMETZ.
